UNITED STATES PATENT OFFICE.

GEORGE C. GARDNER, OF CHICAGO, ILLINOIS.

DESIGN FOR A TRACK FOR DOOR-HANGERS.

SPECIFICATION forming part of Design No. 26,885, dated April 13, 1897.

Application filed February 20, 1897. Serial No. 624,483. Term of patent 7 years.

To all whom it may concern:

Be it known that I, GEORGE C. GARDNER, a citizen of the United States of America, residing at Chicago, in the county of Cook and State of Illinois, have invented a new and original Design for a Track for Door-Hangers, of which the following is a specification.

My invention relates to a certain new and original design for a track for door-hangers, and the like, of which the following is a description.

The drawing presented herewith to illustrate my design is a perspective of a short piece of track, showing the end and the forward side of the same.

Looking at this drawing, said track will be seen to be of substantially even thickness throughout and be composed of a series of longitudinal straight parallel elements and a

series of vertical curved elements, a substantially flat back A, being extended at top and bottom in the form of outward curves $a a'$, continued in the form of hollow cylindrical portions $a^2 a^3$.

The essential features of my invention I consider to be the substantially flat back A, continued at its opposite edges into forwardly-extending curves $a a'$, terminating in substantially cylindrical hollow portions $a^2 a^3$.

I claim as new and desire to secure by Letters Patent—

The design for a track for door-hangers; substantially as shown and described.

GEORGE C. GARDNER.
